UNITED STATES PATENT OFFICE.

JOHN A. HAFNER, OF PITTSBURG, PENNSYLVANIA.

DRIVING-WHEEL.

SPECIFICATION forming part of Letters Patent No. 252,457, dated January 17, 1882.

Application filed December 19, 1881. (No model.)

To all whom it may concern:

Be it known that I, JOHN A. HAFNER, of Pittsburgh, in the county of Allegheny and State of Pennsylvania, have invented a new and useful Improvement in Driving-Wheels; and I do hereby declare the following to be a full, clear, and exact description thereof.

Heretofore the pulley, by means of which the power to drive the runner of a pair of mill-stones was obtained, has been keyed to the spindle of the runner. One great objection to this construction has been that the spindle receives the side pull of the belt, which causes it to wear laterally upon the step in which its lower end is placed, and also to spring. The result is that the spindle is thrown out of perpendicular and the runner out of parallelism with the bed-stone—that is, nearer to it at one edge than at the other. This affects the operation of the stones, causing them to grind imperfectly, and inflicts a serious loss on the miller.

My invention is designed to overcome this difficulty; and it consists in making the spindle independent of the pulley and supporting the pulley in a bearing, which receives the side pull of the belt and takes it off of the spindle, which, being relieved therefrom, remains truly centered and does not tend to get out of alignment.

To enable others skilled in the art to make and use my invention, I will now describe it by reference to the accompanying drawings, in which—

Figure 1 is a vertical section of my improvement. Fig. 2 is a side view of one part of the clutch-coupling which serves to connect the pulley to the spindle. Fig. 3 is a plan view of the pulley and an intermediate coupling-plate which I may use. Fig. 4 is a bottom view of the coupling-plate. Fig. 5 is a section on x , x , Fig. 1.

Like letters of reference indicate like parts. The lower end only of the spindle a is shown. The runner is attached to the upper end (which is not shown) in any known or desired way. The spindle a is stepped in a metallic block, b , which rests upon a lever, c . The lever c is used for adjusting the runner with relation to the bed-stone, to make the mill grind fine or coarse. This is done by raising and lowering the lever c . The block b is placed in a circular open-

ing in the pulley-bearing d , and is provided with a packing-ring to prevent the escape of the lubricating-oil from the central cavity of the bearing. The bearing d has a hollow or tubular body, d' , and a broad base, d'' , between which and the body d' are wings or braces d^3 .

In the sides of the body d' are recesses e , preferably three in number, and in them are iron centering-pieces or followers f , which are concave, as at f' , and filled or faced with Babbitt metal, glass, or other suitable material, f^3 ; or they may be entirely composed of brass or suitable metal. The followers constitute the bearings of the pulley-hub in the hollow body d' , and they are adjusted to it by set-screws f^2 , which extend through the sides of the shell d' . The pulley o has a tubular hub, o' , at one end of which the arms o^2 extend. The arms o^2 run to the middle of the periphery o^3 , and are curved downward, so as to bring the middle of the periphery in the same horizontal plane as the middle of the hub o' . The hub o' and the rest of the pulley are separate pieces, the arms of the wheel running to a ring, o^4 , and they are united by the screws or bolts o^5 running through the flange of the hub into the ring o^4 . If preferred, however, the pulley may be made in one piece. The hollow or center of the hub o' is of greater diameter than that of spindle a , so that the latter may be inserted, operated, and adjusted vertically in the hub without contact or interference with the same. The pulley o imparts its motion to the spindle a through the medium of any driving device which will permit a slight lateral movement of the pulley, such as would be caused by the side pull of the belt and a perpendicular movement of the spindle in adjusting the stones vertically, without interfering with the operation of the pulley or destroying the perpendicularity of the spindle. In the instance shown in the drawings there are two lugs, g , on the ring o^4 of the pulley.

Keyed on the spindle a is a circular plate, h , upon which are also two lugs, h' . The lugs g and h' are not opposite to but at the side of each other. Interposed between them is a sector-plate, i , the wings i' of which are a little less than the distance between the lugs g and h' . The plate i has a center hole, i^2 , through which the spindle a passes, and a groove, i^3 , in

its lower face to let in the heads of the screws o^5 . The wings i' extend between the sides of the lugs g and h' , so that the lugs g bear on the back edges of the wings i' and the front edges of the wings bear on the back edges of the lugs h' . The wings are slightly less in width than the space between the lugs to provide for slight inaccuracies in casting. This construction permits a slight lateral movement 10 of the pulley without affecting the spindle and a slight vertical movement of the spindle without affecting the operation of the pulley, as the lugs can slip radially and axially on the edges i^3 of the plate i enough to compensate for such movement. Any other desired form 15 of clutch device having this characteristic may be used.

To make the vertical movement easier, I have inserted between the moving faces—say 20 i^3 and h' —of the clutch friction-balls p in suitable concavities or slots, q , made in one part, or partially in each. This permits the parts to move easily to the length of the slot q and aids in getting accuracy of adjustment.

25 The pulley and spindle are oiled as follows: An oil-cup, k , is placed at the highest level the oil is to reach, and is connected to the shell d' by a glass tube, k' , and a pipe, k^2 . A hole or holes, n , through the hub o' admits the oil to 30 the spindle and step. Around the lower end of the hub is a plate, m , having sloping sides, to deflect any grit that may be in the oil and prevent it entering the step and cutting the end of the spindle and the step. The oil and 35 grit work under the lower ends of the followers f , which are raised, as at f^2 , high enough for that purpose into the lower ends of the recesses e . The cylinder d' is filled to the proper level through the oil-cup k . The height of the 40 oil is to be seen in the glass tube k' .

Changes may be made in my apparatus. For instance, the arms o^2 need not be curved, but may extend at right angles from the upper 45 edge of the pulley, and the middle of the periphery brought on, or nearly on, the same plane as the middle of the hub. If desired, any other suitable form of oiling apparatus may be used. The outer side of the hub o' is dressed so as to turn easily in the followers. 50 Instead of o being a pulley, it may be a gear-

wheel, if desired, the devices described being advantageously applicable thereto. The use of the friction-balls having a limited vertical movement is applicable to straight-toothed gear clutches generally.

55

What I claim as my invention, and desire to secure by Letters Patent, is—

1. A pulley having a tubular hub, arms extending laterally from one end of the hub, and a periphery the middle of which is on, or nearly on, a level with the middle of the hub, substantially as and for the purposes described.

2. The combination of a pulley having a tubular hub, arms extending laterally at the upper edge, and a hollow bearing in which the hub may turn, substantially as and for the purpose described.

3. The combination of a pulley having a hollow hub, a spindle of less diameter than and operating inside of the hub, and a clutch device connecting the hub and spindle, which permits a slight lateral movement of the pulley and a vertical movement of the spindle, substantially as and for the purposes described.

4. The combination of the hub, the tubular bearing, and adjustable followers placed in the sides of the tubular bearing, substantially as and for the purposes described.

5. The combination of the tubular hub, the deflecting-plate placed on the hub-step, and an oil or grit channel leading away from the step to a suitable receptacle, substantially as and for the purposes described.

6. The combination of a vertical toothed clutch and a loose sector-plate placed between the two parts of the clutch, having wings slightly less in width than the distance between the clutch-teeth, substantially as and for the purposes described.

7. A gear-clutch having straight-sided teeth with friction-balls placed in axially-extending slots in the same, substantially as and for the purposes described.

In testimony whereof I have hereunto set my hand this 16th day of December, A. D. 1881.

JOHN A. HAFNER.
